Primary Examiner — Darcey E Gottschalk*Assistant Examiner* — Vanessa M. Pursley(74) *Attorney, Agent, or Firm* — Kile Park Reed & Houtteman PLLC(57) **CLAIM**

I claim, the ornamental design for a packing box, as shown and described.

DESCRIPTION

FIG. 1 is a top and front perspective view of a packing box, showing my new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view of the packing box showing a state in which an incised side edge portion is inwardly folded.

1 Claim, 8 Drawing Sheets(56)
